INSTRUMENT CONTROL DIAL

Perry H. Rosen, Portland, Oreg., assignor to Electro
Scientific Industries, Inc., Portland, Oreg., a corporation
of Oregon

Filed Nov. 30, 1962, Ser. No. 72,672

Term of patent 14 years

(Cl. D26—1)

Fig. 3.

Fig. 4.

Fig. 1.

Fig. 2.

FIG. 1 is a top plan view of an instrument control dial showing my new design, wherein two dials are used;

FIG. 2 is a side elevational view thereof;

FIG. 3 is a top plan view of another form of the design wherein three dials are used;

FIG. 4 is a side elevational view thereof;

FIG. 5 is a top plan view of another form of the design wherein four dials are used;

FIG. 6 is a side elevational view thereof;

FIG. 7 is a top plan view of another form of the design wherein five dials are used; and

FIG. 8 is a side elevational view thereof.

The dominant features of my design reside in the portions shown in solid lines and comprise the angular index arm in combination with the stacked concentrically mounted dial wheels, all as shown.

I claim:

The ornamental design for an instrument control dial, substantially as shown and described.
